UNITED STATES PATENT OFFICE.

ADOLFO DE CLAIRMONT, OF TOLEDO, OHIO.

SPARK PLUG.

Application filed March 5, 1921. Serial No. 449,965.

To all whom it may concern:

Be it known that I, ADOLFO DE CLAIRMONT, citizen of the United States, residing at Toledo, in the county of Lucas and State of Ohio, have invented certain new and useful Improvements in Spark Plugs, of which the following is a specification.

This invention relates to an improved spark plug for internal combustion engines and has as one of its principal objects to provide a device of this character wherein a condenser will be interposed between the main and ground electrodes of the plug to form primary and secondary spark gaps.

The invention has as a further object to provide a plug wherein the condenser will be formed by a spherical electrode so mounted that a primary spark gap will be provided within the shell of the plug at the upper side of said electrode while secondary spark gaps will be provided exteriorly of the shell at the lower side of the electrode.

A further object of the invention is to provide a plug wherein the condenser will be suspended from the insulator of the plug and wherein the supporting member for said condenser will be so formed and mounted as to parallel the main electrode employed so that current flowing through the main electrode will set up induced currents in said member for surcharging the condenser.

And the invention has as a still further object to provide a plug wherein the condenser as well as the electrodes of the plug may be readily cleaned.

Other and incidental objects will appear hereinafter.

In the drawing:

Figure 1 is a vertical sectional view taken medially through my improved plug,

Fig. 2 is a detail section particularly showing the mounting of the condenser of the plug,

Figure 3 is a fragmentary vertical sectional view illustrating a slight modification of the invention, and

Figure 4 is a fragmentary vertical sectional view showing a further modified structure.

In carrying the invention into effect, I employ a shell 10, the lower end portion of which is externally threaded for engagement in the usual spark plug orifice of an engine cylinder. Formed within the shell is an annular beveled shoulder upon which is arranged a suitable gasket 11 and

seating against said gasket is an insulator 12 of porcelain or other approved material. Surrounding the insulator is a second gasket 13 of approved character and, as will now be observed, the shell is formed at its upper end with a reduced flange or neck 14 which is turned inwardly to coact with said gasket for tightly connecting the insulator with the shell. Surrounding the upper end portion of the insulator above said flange is a protecting sleeve 16 beneath which is arranged a suitable sealing gasket 17 resting upon the flange and overlying said sleeve at its upper end is a similar gasket 18. The sleeve 16 may be formed of any approved material and is designed to protect the projecting upper end portion of the insulator against accidental injury. Extending axially through the insulator is a main electrode 19 provided near its upper end with a cylindrical boss or enlargement 20 having threaded engagement with the insulator and rising from said enlargement is a stud 21 of a diameter somewhat greater than the diameter of the lower end portion of the electrode. Threaded upon said stud to coact with the porcelain is a lock nut 22 and threaded upon the stud to overlie said nut is a cap 23 cupped to accommodate the nut and seating against the gasket 18 for holding the sleeve 16 in position. Above the cap 23, the stud carries a binding nut 24.

The lower end portion of the insulator, below the body thereof, is tapered longitudinally while the main electrode 19 projects below the insulator and suspended from the insulator to coact with said electrode is a spherical condenser 25. This condenser is sustained by a substantially U-shaped supporting member having parallel sides 26 joined by a straight connecting portion 27 and, as will be observed upon reference to Figure 2, the condenser is provided with an eccentric opening therethrough to receive the connecting portion of said member while at the ends of said opening are appropriate notches accommodating the sides of the member. The condenser will thus be held against movement longitudinally of the connecting portion of the member and will also be locked against rotation. The sides of the member are arranged to straddle the main electrode 19 and are embedded in the insulator extending substantially parallel to said electrode, the sides terminating at their upper ends midway of the body of the in-

sulator. The supporting member will thus be securely joined to the insulator without weakening said insulator and, as will now be observed, the member is arranged to support the condenser 25 spaced below the lower end of the main electrode to provide, within the shell 10, a primary spark gap between said electrode and the upper side of the condenser. However, the condenser is disposed to project below the lower end of the shell, the equatorial plane of the condenser being disposed slightly above the plane of the lower end edge of the shell and set into the shell at its lower end to cooperate with said condenser are diametrically arranged ground electrodes 28 providing secondary spark gaps between the lower side of the condenser and said electrodes exteriorly of the shell.

In operation, current flowing through the main electrode will first jump to the condenser to provide a spark at the primary gap between said electrode and the condenser. From the condenser, the current will then jump to either or both of the ground electrodes to form sparks at the secondary gaps of the plug, the interposition of the condenser between the main and ground electrodes operating, as will be well understood, to greatly intensify the sparks given off at the secondary gaps. Further, as will also be readily appreciated, flow of current through the main electrode will set up induced currents in the sides 26 of the supporting member for the condenser and these induced currents will tend to surcharge the condenser for further increasing the intensity of the sparks given off at the secondary gaps. These gaps are located below the lower end of the shell so that when the plug is connected with an engine cylinder, said gaps may be entirely exposed within the combustion chamber of the cylinder. However, fuel gases within said chamber will, of course, rise within the shell so that the spark produced at the primary gap will also serve its function in igniting said gases. Preferably, the lower end of the insulator terminates substantially midway between the beveled internal shoulder of the shell and the lower end of the shell so that a considerable space between the lower end of the insulator and the condenser is thus defined. A brush or cloth may accordingly be easily forced into the lower end of the shell for cleaning the lower end portion of the main electrode as well as also cleaning the condenser. Further, by this arrangement, a pocket of considerable size is provided within the lower end portion of the shell for receiving fuel gases to circulate around the primary spark gap of the plug.

In Figure 3 of the drawing, I have illustrated a slight modification of the invention wherein the insulator, indicated at 29, is removably fitted within the shell, the shell be-

ing indicated at 30. The parts 29 and 30 correspond, of course, to similar parts of the preferred construction and surrounding the insulator is a gasket 31 corresponding to the gasket 13. Threaded into the shell to coact with said gasket is a nut 32 binding the insulator within the shell and, as will be perceived, this nut may be removed for freeing the insulator. Otherwise, this modification is identical with the preferred form of the invention.

In Figure 4, I have illustrated a still further modification. In this figure, the shell is indicated at 33. Embedded in the lower end portion of the insulator, as in the preferred construction, are spaced rods 34 extending in parallel relation to the main electrode 35 and jointly providing the sides of a supporting member for a condenser 36. This condenser is in the nature of a disc and preferably, the rods are threaded into said disc for securing the disc thereon. The condenser 36 corresponds, of course, to the condenser 25 of the preferred construction but is, however, mounted in spaced relation to the lower end of the shell so that the entire surface of the condenser disc is exposed below the shell. In conformity with this arrangement, the main electrode 35 is elongated to project below the shell so as to cooperate with the condenser. Otherwise this modification is identical with the preferred construction.

Having thus described the invention, what is claimed as new is:

1. A spark plug including a shell, an insulator carried thereby, a main electrode extending through the insulator, a spherical condenser suspended from the insulator below the lower end of said electrode in alignment therewith to intersect the plane of the lower end of the shell, the equatorial plane of the condenser being disposed above said first mentioned plane, and a ground electrode upon the shell, to cooperate with said condenser.

2. In a spark plug, the combination of a shell, an insulator carried thereby, a main electrode extending through the insulator, a spherical condenser spaced below the lower end of said electrode to form a spark gap between the electrode and the condenser, and a substantially U-shaped supporting member having sides embedded at their free end portions in the insulator to straddle the main electrode and joined by a connecting portion extending through said condenser supporting the condenser, the condenser having notches therein accommodating the sides of said supporting member whereby the condenser is held against rotation as well as movement along said connecting portion to prevent the length of the gap being varied.

3. In a spark plug, the combination of a shell, an insulator carried thereby terminat-

ing short of the lower end of the shell to define a pocket within the shell below the insulator, a main electrode extending through the insulator terminating within the shell and having its lower end portion exposed within said pocket, a condenser arranged below the lower end of said electrode to operate therewith, a supporting member suspending the condenser from the insulator and provided with sides having exposed portions paralleling the exposed lower end por-

tion of the electrode at opposite sides thereof within said pocket, the space between the exposed portions of said sides and the exposed portion of said electrode being unobstructed, and a ground electrode upon the shell arranged to cooperate with said condenser. 10

In testimony whereof I affix my signature.

ADOLFO de CLAIRMONT, M. D. [L. S.]
